UNITED STATES PATENT OFFICE.

GEORGE M. GRISWOLD, OF NEW HAVEN, CONNECTICUT.

PAPER-BOX-MAKING MACHINE.

SPECIFICATION forming part of Letters Patent No. 429,236, dated June 3, 1890.

Application filed July 7, 1888. Serial No. 279,266. (No model.)

To all whom it may concern:

Be it known that I, GEORGE M. GRISWOLD, a citizen of the United States, residing at New Haven, in the county of New Haven and State 5 of Connecticut, have invented certain new and useful Improvements in Paper-Box-Making Machines; and I do hereby declare the following to be a full, clear, and exact description of the invention, such as will enable others skilled in the art to which it appertains 10 to make and use the same.

My invention relates to certain new and useful improvements in machines for making paper boxes, but more particularly that class 15 of boxes used for the packing of cigarettes, candies, and similar goods, and which primarily consist of an outer case or covering and a drawer, in which the goods are contained and which is designed to slide into the case.

20 The machine herein described shapes and completes the drawer.

The objects of my invention are, first, the formation of the blanks—two at each operation—from a continuous strip of paper fed 25 from a reel or roll to the several combinations of mechanical elements which are to operate thereon in its passage through the machine; second, to properly apply to the paper the glue by which the blanks are 30 finally retained in their finished shape; third, to print upon each blank as it is fed any matter—such, for instance, as the manufacturer's name and address or the quantity or quality 35 of the goods the box is designed to contain; fourth, to automatically crease and fold the cut, glued, and printed blank into the shape in which it is finally to be retained by the 40 glue, and, fifth, to so nest and pack the completed boxes as they come from the machine 45 that the glue which has been applied to them may have ample opportunity to set hard and firm, and the tendency of the folded box, owing to the elasticity of the papers, to return toward its flat position or out of its folded shape in any way be thereby obviated.

This nesting or packing of the completed boxes, as and for the purpose above set forth, is most particularly the object of my present invention, and I do not wish to be confined 50 to the precise details of construction and combination of mechanical devices which I employ in this machine for the accomplishment of that

result, since many changes of the mechanical structure may be made without departing from the spirit and aim of my invention, 55 which contemplates the nesting of each completed box within the one which has next preceded it, so that each shall be firmly held as against change from its completed form.

With these ends in view my invention consists in the structure and organization of mechanical elements, which I will hereinafter 60 fully set forth, and then recite in the claims.

In order that such as are skilled in the art to which my invention appertains may fully 65 understand my improved machine, I will describe the same in detail, reference being had to the accompanying drawings, which form a part of this specification, and in which—

70 Figure 1 is a side elevation of my machine; Fig. 2, a similar view from the other side; Fig. 3, a central vertical longitudinal section; Fig. 4, a plan view; Fig. 5, a detail plan view of the cutting-block and the folding-plate and 75 folding-die; Fig. 6, a bottom plan of the cutter-head and cutters and the folding-plungers. The head, Fig. 6, interacts from above downward upon the plate shown at Fig. 5, as will hereinafter appear. Fig. 7 is a bottom plan of 80 the machine, the printing mechanism being removed; Fig. 8, a detail of the printing mechanism, partly in section; Fig. 9, a detail section through the forward end of the folding plate, plunger, and folding-dies, and showing 85 the carriage upon which the nested boxes are supported and carried downward as they come from the machine; Fig. 10, a plan view of 90 the completed boxes nested and in the position in which they lie upon the carriage; Fig. 11, a perspective of a number of 95 the completed boxes nested and in the position in which they lie upon the carriage; Fig. 12, a partially folded box; Fig. 13, a detail vertical section through the folding-plunger, the sliding carriage, and the ways for the latter, 95 a number of boxes being shown upon said carriage in the position in which they are deposited by the plungers.

Similar reference numbers and letters denote the same parts in all the figures of the 100 drawings.

1 is the frame of the machine, and upon an extension 2 from the end of the said frame is mounted a reel 3, upon which the roll of

blank paper is held, and from which it is drawn between guides 4 and over a roller 5, which is journaled and free to revolve upon a shaft whose bearings are in the frame.

5 From this the strip lettered *x* passes upward to the printing mechanism and thence to the devices, whereby the glue is applied, which mechanisms are operated as follows, reference being particularly had to Figs. 2, 3, and 8.

10 6 is the transversely-extended pulley-shaft which receives motion through the band-wheel 7 through a suitable clutch 8, and 9 is a pinion on the pulley-shaft which meshes with and drives a geared wheel 10, fast upon 15 the main shaft 11. The motion of the main shaft is in the direction indicated by the arrow upon the gear 10 in Fig. 1.

At the end of the main shaft, away from the gear 10, is secured a crank 12, which, 20 through a pitman 13, actuates a bell-crank lever 14. This bell-crank is pivoted upon a short shaft 15, journaled in the side of the frame.

25 16 is a pawl, which is pivotally secured to that arm of the bell-crank operated by the pitman.

17 is a gear secured upon the shaft 15, and 30 18 is a ratchet-wheel secured against the side of the gear last referred to. The to-and-fro movement which the bell-crank derives through the pitman from the main shaft causes the pawl to intermittently rotate the ratchet by engagement with the teeth thereof. As heretofore stated, the gear and ratchet 35 wheels are secured together, so that the latter partakes of the same degree of rotation as the former. The printing-roller 21 is driven by the gear 17 through a smaller gear 19 upon the same shaft 20 as said printing-roller.

40 Upon the periphery of the said printing-roller are arranged in any ordinary manner suitable types for effecting the printing operation. Said types print against the surface of a platen-roll 21^a, over which the paper passes.

45 22 is an ink-fount suitably secured upon the end of the bed. Within the fount is journaled a roll 23, which acts as a distributor for the fount, and receives a slight intermittent rotary movement from a small ratchet- 50 and-pawl mechanism which I have thought it unnecessary to specially describe, but is shown at 24, Fig. 2.

The ink is taken from the distributor by a small roller 25, journaled in a movable frame 55 26 at the under side of the bed of the machine, and by means of a spring 27 said roll is normally held in contact with an intermediate roller 28, which latter rotates against a roller 29. The inking mechanism just described is 60 driven by a small belt 30, which is shown as passing over shaft 6, but which may equally as well be connected to any constantly-rotating shaft in the machine. The roller 29 takes ink from the roller 28 and supplies it to the 65 type-bearing roller. While the roller 25 is in contact with roller 28, which contact is effected by the action of the spring 27 on the

frame, it revolves with it by friction and im-parts ink thereto. At each turn of the machine, however, said roller 25 and its frame 70 are carried along longitudinal of the bed against the action of the spring and into contact with the distributing-roll in the fount. This is effected by means of a toothed wheel 31, secured upon and carried by the shaft 15, 75 and which by engagement with a tooth or pawl 32 on the frame carries the latter along beneath the bed until the roller engages with the distributor in the fount and receives therefrom a portion of ink. When the wheel by 80 continued rotation passes out of engagement with the pawl, the frame and roll are returned to their normal position by the spring 27 and the ink derived from the fount transmitted to the intermediate roller, as hereto- 85 fore described.

The intermediate roller 28 has its bearings beneath the bed of the machine, and for the purpose of more effectual distribution it is given a slight traversing movement from a 90 pivoted bent lever 40, which is actuated by a cam 41, secured to and carried by the toothed wheel 10.

33 is the glue-fount, to which heat is supplied by suitable steam-connections 34. A shaft 95 35 is journaled across the top of the glue-fount, and upon said shaft are secured printing-arms 35^a, which take up glue as they revolve through the fount and apply it from their faces to the paper strip as the latter is drawn over them. Said arms are so placed on the shaft and the shaft so driven that the glue is printed upon the strip at the proper places relative to the cutting and folding operations to which it is subsequently subjected. The shaft derives an intermittent rotation from the bell-crank lever 14 through the pitman 36 by means of a ratchet-wheel 37 and a pawl 38. The ratchet-wheel is fast on the shaft and the pawl pivoted upon a crank 39, whose end is attached pivotally to the extremity of the pitman, and which is also loosely journaled upon the shaft 35. From the glue-printing devices the strip passes outward and around a tension-roller 42, journaled upon a standard or support 43 at some little distance from the machine. The object in carrying the strip outward and around this roller is to give the freshly-applied glue an opportunity to set somewhat before the paper is operated upon by the cutting and folding devices. After returning from the roller to the machine the strip is introduced upon the flat top of the bed and passes between guides 44 to the slitting and feeding rollers 45, which divide the paper longitudinally into two strips of equal width, and also by their grasp upon said paper feed it along intermittently as is required.

The slitting operation is necessary, since in 130 the machine shown and described herein the operating mechanism is in duplicate and simultaneously produces boxes at each operation. The slitting and feeding rolls just re-

ferred to are journaled one above the other, the under roll with its periphery just flush with the surface of the bed. The lower roll is driven from the gear 17 through the gear 46, which by engagement with a duplicate thereof imparts synchronous movement to the upper roll.

47 is the slitting-knife, which is secured about the center of the upper roll. It runs 10 against a shoulder upon the lower roll and thereby severs the paper by a shear cut. When the paper has been slitted, the rolls feed the two strips forward beneath the cutting-dies, which descend and blank out the 15 paper into the shape shown at Fig. 10, those portions which constitute the scrap or waste, and are driven downward and permitted to escape through openings in the cutting-block, which appear at Fig. 5 and are numbered 49. 20 The die, simultaneously with the blanking operation, creases the blank in the proper places for the folding up thereof into completed form, as shown by dotted lines at Fig. 10. Flat springs 50, secured to the face of 25 the dies, serve to hold the cut blanks down upon the bed as the dies ascend. The blanking operation forms the blank complete, except that it does not sever it from the strip at the line *a*, Fig. 10. Said blank is left thus 30 connected, so that it may be fed forward with the strip by the push of the feeding-rolls into position for the final operation of folding. The final severing is effected simultaneously 35 with the bending up of the sides and ends of the blank by the plungers.

The downward-cutting movement of the dies 48, whereby the blank is cut as aforesaid, is effected through a lever 51, which is hung longitudinally beneath the bed, and is 40 operated in proper time by its engagement through a stud with a profile cam 52 on the main shaft, a cross-head 53, and links 54, which connect the ends of the cross-head with the cutter-head 55, on which the dies are 45 mounted. The said cutter-head slides upon ways formed on the upward extension 56 on the frame. When the blanking-dies have been raised out of engagement with the cutter-block, the shaped blank is fed along to a 50 position over the folding-dies 57. (Shown at Fig. 5.)

It is here proper to state that the folding of the blank shown at Fig. 10 into the shape shown at Fig. 12 is accomplished by first 55 trimming the ears A upward at right angles to the face of the blank and then bending the side flaps B, of which the ears A form a part, upward at right angles to the blank. This last operation leaves the ears A projecting inward across the face of the blank and edgewise toward it. The creased end 60 apron C is then folded upward and its end flap, to which the glue has heretofore been applied, as described, doubled over upon itself 65 and upon the ears A, whereby the box is retained in the position shown at Fig. 12. The upward turning of the ears A is effected by

means of folding-feet 58, which are formed upon the die-block and move with said block.

As will be understood, the operation of the feet upon the blank is always one step behind that of the cutting-die—that is to say, their operation upon the cut blank is simultaneous with the cutting out of the next succeeding blank from the strip. These folding-feet bend up the ears A against the edges of blocks 59, below the plane of which the faces of the feet pass in their descent.

Having performed the operation of folding the ears upward the feet ascend with the cutter-head, and the plungers 60, whose shape is shown in the plan view, Fig. 6, descend upon the blanks and drive the latter down into the folding-dies shown at Fig. 5. This operation turns up the edges B and the end flap C, and causes the ears A to assume the edgewise position toward and across the face of the blank shown at Fig. 12. A small straight-edged cutter 80, secured at the rear of each plunger on the cutter-head, severs the blank 90 finally from the strip previous to the downward action of the plungers.

In Figs. 5 and 9 are shown springs 87, secured at the sides of the die-openings. The function of these springs is to elevate the 95 strips of paper between and at the sides of the blanks, so that said strips may not be carried downward by the plungers.

The plungers are mounted upon extremities of rods 62, supported in guideways in the 100 upward extension of the frame. The properly-timed vertical reciprocation of these rods is obtained from a profile-cam 63 on the main shaft through a lever 64, operated by said cam through a stud or roll connection, an upwardly-extended connecting-rod 65, a rock-arm 66, to which said rod is attached, a journaled rock-shaft 67, upon which the arm 66 is mounted, and an arm 68, which is connected to a cross-head 69, secured to the plunger- 110 rods.

After the blank has been driven down into the folding-die, there remains only to fold the glue-coated apron C over upon itself and upon the inwardly-turned ears, so that the 115 glue, by adhesion to the parts just specified, may hold the box in shape. This folding operation is effected by means of a pair of folders 79—one for each box—which are operated from beneath the bed. These folders are shown at Fig. 9, and their movement and method of operation are as follows: They have a quadruple movement—first, upward to a plane higher than the edge B of the box as it lies in the die; second, forward 120 toward and past the edge of the box to turn over the end of the apron; third, downward to complete the folding of the end of said apron, and, fourth, backward to firmly compress the turned, folded, and glued end of 125 said apron against its own lower portion and against the inwardly-turned ears, so that the ears and the double end of the box formed by the apron are firmly held together by the 130

glue. As the side flaps B are connected by the ears to the end of the box (see Fig. 12) they are thereby held in their bent position at right angles to the bottom of the box. It will be perceived that the front ends of the plungers are cut away as to their central portions, so as to leave only the narrow projections 85. (See Fig. 6.) The folders work between these projections, while the plungers still hold the boxes firmly in the dies. The upward movement of these folders is derived from a cam 70 on the main shaft through a lever 70^a, which is operated by said cam like the levers heretofore referred to, and whose end projects under and is adapted to raise the standard 71, on which the folders are mounted. The lower end of this standard has a sliding connection with two pins 72, mounted upon a rock-shaft 73, and this shaft receives from a lever 74, operated by a cam 74^a on the main shaft, the movement which it imparts in the form of forward and back motion to the folders. Thus the combined action of the two cam-actuated levers just described imparts to the said folders the compound movement whereby the final holding is effected in the box. The varying positions of the folders is shown in dotted lines at the detail, Fig. 9. When the box has been thus folded in the die, its bottom rests upon a small carriage 75, which is adapted to slide upon an inclined way 76, and is normally held against the bottom of the lowermost box by the pull of a counter-weight 77. The box first made, as will be readily understood, rests directly upon this carriage. The second is thrust into the first, the third into the second, &c., and as the boxes are thus piled one within another (see Fig. 11) the carriage is forced downward along its way against the pull of the counter-weight and forming a support for the stack or nest of boxes. The boxes are prevented from rising off the carriage by a shield 78, which projects downward parallel to the ways upon which the carriage runs. When the carriage has been pushed to the end of its track by the boxes, those at the bottom may be removed, and the carriage will be drawn upward against the now shortened pile of boxes, so as to support them. I find, however, that it is unnecessary in practice to remove the boxes, since they will, after the carriage and way are filled, rise over the end of the carriage and fall by gravity into a basket or other receptacle prepared for them. By this means the freshly-glued boxes are tightly held in the pile for a period of time sufficient to allow the glue to set firm and hard enough to obviate any danger of the box ungluing or becoming misshapen by the elasticity of the paper.

In the operation of the machine it is to be understood that the intermittent movements by which the printing-roller, the gluing mechanism, and the feeding and slitting rolls are actuated are all so timed as to admit of the properly-timed action of the blanking and

the folding mechanism. The feeding and slitting rolls, operated as hereinbefore described through the bell-crank lever 14 and the parts 15, 16, 17, and 18, draw forward the paper strip, and during this forward feeding the printing and the application of the glue are effected. Meanwhile the blanking and folding mechanisms are at rest. When the feeding ceases, the cutter-head descends and blanks the strip, and simultaneously the folding-feet bend up the ears on the blank cut out by the previous operation of the dies. Then as the cutter-head ascends the plungers descend and force the blank just operated on by the folding-feet into the die, where, before the plungers recede, the folders complete the box. Then the feeding recommences and the blank paper for the next box is brought under the die and the cut blank fed forward for the folding devices.

I claim as of my invention—

1. In a machine of the character described, the combination, with the blanking and folding devices, of an open die, and a folding-plunger adapted to co-operate with said die for the folding of the box, a movable carriage, and a way upon which said carriage may travel located beneath the plane of the die and adapted to support the boxes as the same are folded and thrust downward, and means whereby said carriage is upheld against the boxes and is caused to ascend into contact with said boxes when a portion of the latter have been removed, substantially as described.

2. In a machine of the character described, the combination, with the folding-plunger, and the open-bottomed die adapted to co-operate with said plunger, of an inclined way beneath said die, a carriage mounted upon said way, means for imparting to said carriage a movement toward the top of the way, and a shield adapted to engage the pile of boxes from above, substantially as described.

3. The carriage located beneath the open-bottomed folding-die and adapted to receive the boxes as the latter are thrust downward through the die, as described, in combination with the ways upon which said carriage is supported, and the counter-weight whereby said carriage is normally held at the top of the ways beneath the die, substantially as set forth.

4. In a machine of the character described, the combination, with the open-bottomed die and the folding mechanism operating conjointly therewith, of a carriage arranged in a plane beneath the die and adapted to move both downward and outward away from said die, ways upon which said carriage is supported, and means for imparting upward movement to said carriage, substantially as set forth.

5. The combination, in a machine of the character described, with the feeding and slitting rolls intermittently operated upon the bed, of the blanking die and block arranged

behind the rolls and adapted to blank the strip, the folding-feet secured upon the cutter-head and moving therewith, and the vertically-moving folding-plungers and the eccentrically-operating folders arranged to act upon the box *seriatim* after the operation of the folding-feet, substantially as set forth.

6. The combination, with the intermittently-operated feeding and slitting rolls, of the vertically-reciprocating cutter-head arranged behind the said rolls and carrying both the cutter-dies and the folding-feet, the vertically-reciprocating plungers, the open-bottomed die, into which said plungers descend, the eccentrically-movable folders operated from below the bed of the machine, and the movable carriage arranged beneath the die and upon which the boxes are successively nested or packed by the plungers, substantially as set forth.

7. In a machine of the character described, the combination, with the feeding-rollers and the cutting devices carried upon said rolls, and whereby the strip of paper is longitudinally divided, of the vertically-actuated cutter-head carrying the blanking-dies and creases and the severing-knife and having the feet for effecting the preliminary folding mounted thereon, the vertically-actuated plungers, the folding-dies, into which the plungers descend to fold the box, the folders having the fourfold motion, whereby the end of the box is folded and secured, and the carriage arranged beneath the folding-die, whereon the completed boxes are deposited in nested form, substantially as shown and described.

8. In a paper-box-making machine, the combination, with the folding-die and a plunger adapted to force the blanks downwardly into said die, of an inclined way extending downward and outward beneath said die, a carriage having a floor parallel to the face of the die and arranged upon said way, means for imparting movement to said carriage, and a shield extending downward and outward above said way and adapted to retain the nested boxes upon the carriage, substantially as specified.

9. In a machine of the character described, the combination, with the open-bottomed die and the plunger operating in conjunction therewith, of a movable carriage arranged beneath said folding-die, the ways upon which said carriage is mounted, the shield arranged above the carriage for the holding of the boxes thereon, and means, as a counter-balance, whereby said carriage is normally retained beneath the folding-die at the top of its ways, substantially as specified.

10. The combination, with the blanking and folding devices, substantially as specified, of a carriage arranged beneath the folding-die, an inclined way upon which said carriage may travel, and means, as a counter-weight, whereby said carriage is normally retained at the top of its track, the floor of said carriage being so-placed relative to the ways as

to be parallel to the plane of the folding-die, whereby a flat surface is afforded for the support of the boxes, substantially as described.

11. In a machine of the character described, the combination, with the feeding and slitting rolls and means for imparting thereto an intermittent rotary movement, of the support for the roll of blank paper, a pair of printing-rollers engaging and adapted to print the strip, a glue-printing wheel adapted to operate upon said strip and to impart glue thereto, and a tension-roller separated a little distance from the machine and over which the strip may pass, whereby the glue and ink may become somewhat set prior to the action of the forming devices, substantially as set forth.

12. The combination, with the plungers and the folding-dies within which said plungers descend, said plungers having projections of the folders and their standards, and the duplex cam and lever system arranged beneath the bed, and whereby the compound folding movement is imparted to the folders, substantially as specified.

13. The combination, with the folders and their standards, of the cam-actuated rock-shaft, upon which said standards are supported by a sliding connection, said rock-shaft adapted to impart to said standards and folders their to-and-fro movement, and a cam-actuated lever projecting under the said standards and whereby the vertical movement is imparted thereto, substantially as specified.

14. The combination, with the plungers having the projections of the folding-dies, within which said plungers descend and fold the box, the eccentrically-actuated folders arranged at the end of the folding-dies and adapted to operate between the projections to complete the folding of the apron, and the movable carriage arranged beneath the folding-dies and whereon the boxes are deposited by the plungers and upheld during the action of the folders, as set forth.

15. In a machine of the character described, the combination, with the folding-die and the plunger adapted to co-operate therewith, of an upwardly-projecting folder arranged at the forward end of the die and provided with a depending portion adapted to operate on the end flap of the box, and means, as described, whereby said folder is operated to effect its required four movements, substantially as specified.

16. The combination of the cutting devices, the plunger, the die located beneath the latter, the four-motion folder, and the movable carriage upon which the boxes are deposited, substantially as set forth.

17. In a machine of the character described, the combination, with the folding-die and the reciprocating plunger adapted to co-operate with said die, said plunger being cut away at its forward end, of folding devices adapted to act upon the end flap of the box and operating in the cut-away portion of the plun-

ger, and means, as described, whereby the proper movements of the folder are effected, substantially as described.

18. In a machine for making paper boxes,

5 the combination, with the open folding-die, the plunger adapted to co-operate therewith, and means for operating the plunger, of the vertically-reciprocating die-block, cutting devices secured upon said block, and folding-
10 feet carried by said die-block, adapted to turn up the ears A of the blank, substantially as described.

19. In a machine of the character described, the combination, with a die-block provided
15 with blanking-dies, and also with mechanism for effecting a partial folding of the blank cut by said dies, of a folding-plunger and a die adapted to co-operate therewith, said folding-
20 plunger adapted to operate one step behind the cutting-dies, substantially as described.

20. In a machine of the character described, the combination, with the die-block having thereon means for blanking and for severing and for partially folding the stock, and means
25 for imparting vertical reciprocation to said die-block, of a folding-die located in the path of the stock and ahead of the blanking-die, a plunger adapted to co-operate with said die, and means, as described, whereby said plun-
30 ger is operated alternately with the die-block, substantially as described.

21. In a machine of the character described, the combination, with feeding-rollers, and means for imparting thereto an intermittent
35 movement, of a die-block having suitable blanking-dies located in front of the feeding-rollers, a folding-die and a folding-plunger adapted to co-operate therewith and located in

front of the die-block, and the folder arranged at the end of the plunger and adapted to operate upon the end flap of the box, substantially as described.

22. In a machine of the character described, the combination, with the support for the roll of paper, and means, as described, whereby
45 said paper is conducted to the operating devices and is drawn forward, of the glue-fount 33, secured to the frame of the machine, a glue-printing wheel journaled across the glue-fount and having radial glue-printing arms adapted
50 to take up glue from the fount and to imprint said glue upon the surface of the traveling strip, a ratchet secured upon the glue-wheel shaft, a pawl engaging said ratchet, and means, as described, connected to the operating mechanism of the machine for imparting to said wheel through said pawl a rotary movement, substantially as set forth.

23. In a machine of the character described, the combination, with the open-bottomed die,
60 the plunger adapted to force the cut blanks downwardly into said die, and the folding mechanism, of a carriage arranged beneath the die and adapted to receive and support the boxes in nested form as said boxes are
65 thrust downward, said carriage having liberty of movement downward and outward from beneath said die, whereby piles of boxes of various heights may be supported.

In testimony whereof I affix my signature in
70 presence of two witnesses.

GEORGE M. GRISWOLD.
